DISPLAY BOARD

Daniel P. Novak, Parkridge, and David R. Main, Glenview, Ill., assignors to Frank Mayer & Associates, Grafton, Wis., a corporation of Wisconsin

Filed Nov. 12, 1969, Ser. No. 20,040

Term of patent 14 years

Int. Cl. D20—03

U.S. Cl. D96—12

FIG. 1 is a perspective view of a display board embodying our new design;

FIG. 2 is a front elevational view thereof;

FIG. 3 is a top view thereof;

FIG. 4 is a right elevational view thereof, the left side being a mirror image;

FIG. 5 is a rear elevational view thereof; and

FIG. 6 is a bottom plan view thereof.

We claim:

The ornamental design for a display board, substantially as shown and described.
